UNITED STATES PATENT OFFICE.

ELSA K. BUEDINGEN, OF NEW YORK, N. Y., ASSIGNOR TO PRIDDY & BUEDINGEN, A COPARTNERSHIP COMPOSED OF MARGARET D. PRIDDY AND ELSA K. BUEDINGEN, BOTH OF NEW YORK, N. Y.

DESIGN FOR A TEA COZY.

Application filed November 11, 1924. Serial No. 11,342. Term of patent 7 years.

To all whom it may concern:

Be it known that I, ELSA K. BUEDINGEN, a citizen of the United States, residing at the city, county, and State of New York, have invented a new, original, and ornamental Design for a Tea Cozy, of which the following is a specification, reference being had to the accompanying drawings, forming part thereof, in which—

Fig. 2 is a bottom plan view thereof.

I claim:

The ornamental design for a tea cozy, substantially as shown.

ELSA K. BUEDINGEN.
